UNITED STATES PATENT OFFICE.

LEWIS B. BRIDGES, OF BROOKLYN, NEW YORK, ASSIGNOR TO RAMP BUILDINGS CORPORATION, OF NEW YORK, N. Y., A CORPORATION OF DELAWARE.

BUILDING.

Application filed January 31, 1921. Serial No. 441,888.

To all whom it may concern:

Be it known that I, LEWIS B. BRIDGES, a citizen of the United States, and resident of the borough of Brooklyn, in the county of 5 Kings, city and State of New York, have invented certain new and useful Improvements in Buildings, of which the following is a specification.

This invention relates to improvements in 10 buildings of the type in which groups of vertically staggered floors are connected by ramps.

One object of the present invention is to provide an arrangement of the ramps and 15 groups of floors affording maximum economy of floor space.

A further object of the invention is to provide a building, especially adapted for use 20 for storage purposes, so constructed that vehicles may travel in a direct line to or from any floor of the building.

Another important object of the invention is to provide a building having groups of relatively staggered floors connected by 25 ramps in such a way that any floor, or any combination of floors, of either or both groups may be isolated in case of fire without preventing egress from all the remaining floors to the street by way of the ramps.

30 Other objects of the invention are to provide a building having floors connected by ramps so constructed that ascent and descent from floor to floor is greatly facilitated, that the distance of travel from the 35 lowermost to the uppermost floor is reduced to a minimum, and that the building may be used for many different purposes.

In the drawings:

Fig. 1 is a section on the line I—I of Fig. 40 2, showing one form of building embodying the invention;

Fig. 2 a vertical section on the line II—II of Fig. 1;

Fig. 3 a vertical section on the line 45 III—III of Fig. 1;

Fig. 4 a vertical section on the line IV—IV of Fig. 2;

Fig. 5 a vertical section on the line V—V of Fig. 2;

50 Fig. 6 a horizontal section on the line VI—VI of Fig. 7, showing a modified construction;

Fig. 7 a vertical section on the line VII—VII of Fig. 6;

Fig. 8 a vertical section on the line 55 VII—VIII of Fig. 7;

Fig. 9 a vertical section on the line IX—IX of Fig. 7;

Fig. 10 a fragmentary vertical section on an enlarged scale showing one of the fire 60 doors closed; and

Fig. 11 a section on the line XI—XI of Fig. 10.

In the construction shown in Figs. 1 to 5 the building is divided into two parts by a 65 dividing wall 3 parallel with the side walls 2 and extending from one end wall 1 to the other end wall 1. Two groups of super- 70 posed floors 4 and 5 are located at opposite sides of the wall 3, the floors 5 being located in planes intermediate the planes of the floors 4. A roof section 6 overlies the group of floors 4 and a roof section 7 overlies the group of floors 5. A suitable door 8 affords access to the lowest floor 4 through one end wall 1 75 at a point preferably alongside the dividing wall 3, as shown. The four outer walls of the building are provided with suitable windows 9.

A series of longitudinally aligned and stepped ramps 10 extends diagonally upward along one side of the wall 3, preferably at that side of the wall upon which floors 4 are located. The lower end of the lowest ramp joins the lowest floor 4 a short 80 distance from the adjacent end wall 1 and opposite the door 8, while the upper end of the highest ramp joins the uppermost floor 4 a short distance from the opposite end wall 1, the spaces between the ends of these 85 ramps and the end walls forming landings 11 on the first and third floors 4 at opposite ends of the series of ramps. A third landing 11 connects the adjacent ends of the second and third ramps, said landing 11 com- 90 municating with the second floor 4 and being in effect a part or extension of said floor. Two landings 12, forming parts or extensions of the two floors 5, connect the adjacent ends of the first and second ramps 100 and the third and fourth ramps, respectively.

Doorways 13 in the dividing wall 3 give access to the floors 5 from the landings 12. I prefer to provide a side wall 14 and 105 stepped top wall 15 for the series of ramps, thus forming a stepped, chute-like, passage extending diagonally upward through the

building from one wall 1 to the other wall 1, and to provide doorways 16 in the side wall 14 giving access from the landings 11 to the floors 4. It will be observed that in the construction shown, part of wall 3 forms one side wall of the chute-like passage and that parts of the floors 4 form part of the top wall or ceiling of the passage, thus materially reducing cost and labor in the construction of this enclosed passage or driveway.

I prefer to provide suitable steel fire doors 17 for closing the doorways 13 and 16. Any suitable known forms of fire doors may be employed, said doors being either manually 15 or thermally controlled, as desired. I have shown a well known form of flexible steel door of the roll-up or curtain type. In Figs. 10 and 11, which are detail views of the lower end of the chute, I have shown 20 one of these doors in closed position. It will be obvious that, with the construction above described, any floor or combination of floors upon which a fire occurs may be isolated without preventing persons, vehicles, or the 25 like from passing in safety down the ramps to the street from all the remaining floors.

The construction shown in Figs. 1 to 5 is particularly adapted for relatively long and low buildings, while the modified construction 30 shown in Figs. 6 to 9 may be advantageously employed in buildings of any height and erected on plots of any size or shape. The building shown in Figs. 6 to 9 comprises end walls 1, side walls 2, a dividing wall 3, groups of vertically staggered floors 4 and 5, and a door 8 giving access to the lowest floor 4 at one side of wall 3, these walls, floors, and door 8 being arranged in the same manner as in the building 35 shown in Figs. 1 to 5.

In this modified construction superposed pairs of ramps 18 are provided, preferably located at that side of wall 3 at which floors 4 are located. The two ramps forming each 45 pair of ramps are arranged in stepped relation and in longitudinal alignment, so that each pair of ramps connects one of the floors 5 with the next higher and lower floors 4. A landing 19 connects the adjacent ends of 50 each pair of ramps, said landings 19 forming parts or extensions of floors 5. Landings 20 are located at the other ends of the two ramps, said landings forming parts or extensions of floors 4.

55 Any suitable guard rail or other protecting means may be provided along the edges of ramps 18 and landings 20 opposite wall 3. I prefer, however, to provide a guard or dividing wall 21 parallel with wall 3 from 60 top to bottom of the building, so that the pairs of ramps and landings 19 and 20 will form in effect a series of superposed chute-like passages, each set of ramps and landings forming a top wall or ceiling overlying 65 the next lower set of ramps and landings.

Doorways 22 in wall 3 give access to floors 5 from landings 19, and doorways 23 give access to floors 4 from landings 20. The doorways 22 and 23 are preferably equipped with firedoors 17 similar to those heretofore described in connection with the building shown in Figs. 1 to 5 and Figs. 10 and 11. It will be obvious, however, that any other type of firedoor may be employed.

In the building shown in Figs. 6 to 9, vehicles or persons entering door 8 may pass through the adjacent doorway 23 to the lowest floor 4 or ascend the ramps to any desired floor of either group, traversing floors 4 between the highest ramp of each pair to the lowest ramp of the next higher pair of ramps. The space on the various floors may, if desired be subdivided in any suitable manner into rooms, storage spaces for motor vehicles, or the like, a path, corridor or driveway being of course provided on each floor 4 to permit free passage between the ends of adjacent pairs of ramps.

While I have shown only two constructions, it will be understood that the invention 90 is not limited to the constructions shown, as the shape and relative arrangement of the two groups of floors and the ramps may be considerably varied without departing from the invention.

What I claim is:

1. A building comprising two groups of superposed floors overlying different parts of the ground area of the building, the floors of one group being arranged in planes 100 intermediate the planes of the floors of the other group, and a progressive series of similarly inclined ramps along the adjoining sides of the two groups of floors, said floors each having a portion connecting two adjacent ends of two of said ramps and cooperating with the ramps to form a continuous passageway connecting all the floors.

2. A building comprising outer walls, two groups of superposed floors overlying different parts of the ground area within the outer walls, the floors of one group lying in planes intermediate the planes of the floors of the other group, and a stepped series of ramps extending along the adjoining sides 115 of the groups of floors and connecting all of the floors.

3. A building comprising outer walls, two groups of superposed floors overlying different parts of the ground area within the outer walls, the floors of one group lying in planes intermediate the planes of the floors of the other group, and a series of similarly inclined ramps parallel with the adjacent sides of the two groups of floors, 125 each of said ramps connecting two floors of different groups.

4. A building having two groups of floors overlying different parts of the ground area of the building and arranged with the floors 130

of one group in planes intermediate the planes of the floors of the other group, said building having a straightaway driveway communicating with all the floors thereof.

8. 5. A building comprising outer walls, a dividing wall, two groups of superposed floors at opposite sides of the dividing wall, the floors in one group being located in planes intermediate the planes of the floors 10 in the other group, and a stepped series of similarly inclined ramps extending along one side of the dividing wall and connecting all of the floors together, portions of floors of different groups being located at opposite ends of each ramp of the series, and said dividing wall being provided with doorways giving access to the ramps from the floors at the opposite side of the dividing wall at the points where said floors are extended between the ends of adjacent ramps.

6. A building comprising outer walls, two groups of vertically staggered floors, a dividing wall separating the groups of floors, a series of similarly inclined ramps extending upward from floor to floor along one side of the dividing wall through one group of floors, each floor at the opposite side of the dividing wall from the ramps having an extension connecting the same with the adjacent ends of two ramps and the dividing wall being provided with doorways at said extensions, and a guard wall at the opposite side of the series of ramps from the dividing wall having doorways therein opening upon the floors of the group through which the ramps extend.

7. A building comprising outer walls, two groups of vertically staggered floors, a dividing wall separating the groups of floors, 40 a series of similarly inclined ramps extending upward from floor to floor along one side of the dividing wall through one group of floors, each floor at the opposite side of the dividing wall from the ramps having an extension connecting the same with the adjacent ends of two ramps and the dividing wall being provided with doorways at said extensions, a guard wall at the opposite side of the series of ramps from the dividing wall having doorways therein opening upon the floors of the group through which the ramps extend, and fire doors for closing the doorways in the dividing wall and guard wall.

8. A building comprising outer walls and two groups of superposed horizontal floors overlying different parts of the ground area within said walls, the floors of one group being located in planes intermediate the planes 60 of the floors of the other group, and means cooperating with the floors in one of said groups to form a continuous passageway located entirely within the bounds of the edges of the floors of said group and connecting all the floors of the two groups, said pas-

sageway having horizontal portions and inclined portions intermediate the horizontal portions, and the alternate horizontal portions of the passage being contiguous with floors of different groups located at progressively higher levels.

9. A building having two groups of floors arranged side by side, the floors of one group being located in planes intermediate the planes of the floors of the other group, 75 and means forming a continuous straightaway enclosed passage extending along the inner side of one group of floors having alternate horizontal and inclined sections, the bottom walls of the horizontal sections 80 of the passage communicating alternately with floors of different groups at progressively higher levels, the side walls of the passage being provided with doorways giving access from the horizontal sections of 85 the passage to the floors at the levels of said sections, and fire doors for closing said doorways.

10. A building comprising groups of superposed floors overlying different parts of 90 the ground area of the building, the floors of different groups being located in different horizontal planes, means forming a straightaway enclosed driveway having doorways in the sides thereof communicating 95 with all the floors, and fire doors for closing said doorways.

11. A building having two groups of superposed floors, the floors of one group being located in planes intermediate the planes 100 of the floors of the other group, and a plurality of similarly inclined ramps parallel with the adjoining sides of the two groups of floors and connecting all of the floors, each floor of one group being connected by two of 105 said similarly inclined ramps with the next higher and lower floors of the other group.

12. A building having two groups of superposed floors, the floors of one group being located in planes intermediate the 110 planes of the floors of the other group, and a plurality of similarly inclined ramps connecting all of the floors, each floor of one group being connected by two of said similarly inclined ramps with the next higher 115 and lower floors of the other group, and all of said ramps being located in the same vertical plane.

13. A building having two groups of superposed floors, the floors of one group being located in planes intermediate the planes of the floors of the other group, outer walls surrounding the groups of floors, a dividing wall separating the groups of floors, and a plurality of similarly inclined ramps all located along one side of the dividing wall and extending parallel with said wall, each floor of one group having an extension projecting through an opening in the dividing wall and having opposite sides thereof con- 130

nected by two of said ramps with the next higher and lower floors of the other group.

14. A building having two groups of superposed floors, the floors of one group being located in planes intermediate the planes of the floors of the other group, outer walls surrounding the groups of floors, a dividing wall separating the groups of floors, a plurality of similarly inclined ramps all located along one side of the dividing wall and extending parallel with said wall, each floor of one group having an extension projecting

through an opening in the dividing wall and having opposite sides thereof connected by two of said ramps with the next higher and lower floors of the other group, and a guard wall parallel with the dividing wall extending along the outer edges of the ramps and provided with openings communicating with the floors which are located at the same side 20 of the dividing wall as the ramps. 15

In testimony whereof I hereunto affix my signature.

LEWIS B. BRIDGES.
